UNITED STATES PATENT OFFICE.

EDWARD P. DANDRIDGE, OF PHILADELPHIA, PENNSYLVANIA.

TWINE-HOLDER.

No. 884,799.

Specification of Letters Patent.

Patented April 14, 1908.

Application filed October 10, 1907. Serial No. 396,773.

To all whom it may concern:

Be it known that I, EDWARD P. DANDRIDGE, a citizen of the United States of America, residing at Philadelphia, in the county of Philadelphia and State of Pennsylvania, have invented new and useful Improvements in Twine-Holders, of which the following is a specification.

This invention relates to twine holders, designed for the purpose of facilitating the work of weighing goods, placing the goods in a paper bag of the required size and tying a cord or twine about the package and cutting the twine.

One of the principal objects of the invention is to provide a simple and convenient device for the use of grocers and merchants generally handling goods requiring to be weighed and packaged in paper bags.

Another object is to provide a device of the character referred to with a cabinet or series of compartments for paper bags, a series of spools containing wrapping twine, a scale for weighing goods and a funnel support for filling the bags.

These and other objects may be attained by means of the construction illustrated in the accompanying drawings, in which:—

Figure 1 is a plan view of the device. Fig. 2 is a front view of the same. Fig. 3 is a detail perspective view of the spindle upon which the spools are placed for winding the twine thereon. Fig. 4 is an end view of the device. Fig. 5 is a front to rear vertical section. Fig. 6 is a detail perspective view showing the spindles for the twine spools.

Referring to the drawings for a more specific description of my invention, the numeral 1 designates the bottom of the frame, and 2 is a platform for supporting the scales 3. The front 4 of the frame is provided with an opening 5 in the center thereof and an aperture 6 cut from the bottom of said front. A pair of parallel supports 7 are secured to the bottom 1, and one of said supports is provided with a longitudinal groove 8 in its upper edge. At intervals the supports 7 are provided with means for supporting pintles 9 for the twine spools, said pintles being seated at one end in the recess 10 in one of the supports 7. The pintles are each provided with a flattened portion 11 having an aperture therein through which a rod 12 passes, said rod being seated in the groove 8. A recess 13 is formed in one of the supports 7, and the pintle is provided with an upwardly

extending arm 14 having a thumb piece 15 formed upon its upper end. The result of this structure is that any one of the twine spools may be readily removed by placing the thumb or finger upon the thumb piece 15 and tipping the spool out of the case or frame. The twine spools 16 are placed upon the pintles 9, and the twine 17 is wound upon the spools and led out through the openings 6 in position to be used. A twine cutter 18 is secured to the front 4. A platform 19 for supporting the bags while they are being filled is hinged at 20 to the bottom 1, and a funnel support 21 is hinged at 22 to the top 70 of the front 4.

For winding the twine from the balls to the spools I have provided a shaft 23 provided with a gear wheel 24 at one end and at the opposite end provided with a spindle 25 secured to a block 26 having projecting pins 27. Projecting from the block 26 is a bearing 28 connected to the bifurcated end of the shaft 23 by means of a set screw 29. Whenever it is required to wind the twine from the balls to the spools one of the spools is placed on the spindle 25 with the pins 27 projecting into holes in the spool. A stub shaft 30 mounted in the frame is provided with a gear wheel 31 which meshes with the wheel 24, and a handle 32 on the wheel 31 serves to rotate the same and through the gear wheel 24 rotates the shaft 23 and the spindle 25. Thus the twine is wound upon the spools from the balls, and after the winding operation the screw 29 may be loosened and the spindle 25 swung into the position shown in dotted lines in Fig. 1 out of the way with the end of the spindle resting in a hook or other support 33.

The paper bag holder consists of a series of compartments 34 for bags of different sizes, said compartments being open at the front side and closed at the back and ends and provided with partitions 35 at suitable intervals. The paper bag holder is secured to the bottom 1 of the frame by means of L-shaped keepers 36.

The operation of my invention may be briefly described as follows: Whenever it is required to weigh and package goods of a granular character, the goods being weighed on the scales 3 are discharged in the funnel a, a paper bag of suitable size being connected to the funnel to receive the goods. The end 110 of the twine 17 is used for tying up the package, and the twine cutter 18 is used for cut-

ting the twine. Whenever it is required to fill the empty spools 16 they are placed upon the spindle 25 and filled from an ordinary ball of twine.

5 My device is of comparatively simple construction, is convenient and desirable for use in weighing and packaging goods, and the cost of its production is comparatively slight.

Having thus described the invention, what 10 is claimed as new, is:—

In a device of the character described, a series of spools for carrying twine, said spools each being mounted upon a spindle support-

ed at one end in a bar secured to the frame, a flattened portion having a hole therein, a rod 15 extending through said hole and supported in a groove in one of the frame bars, and a thumb piece for tipping said spindle to remove the spool therefrom.

In testimony whereof I affix my signature 20 in presence of two witnesses.

EDWARD P. DANDRIDGE.
